[57] ABSTRACT

A method of forming an expanded structural member, and a structural member formed thereby, wherein spaced parallel longitudinally extending rows of openings are pierced in a web of a member of ductile metal which has a constant cross-sectional shape, the openings of each row overlapping those of the next adjacent row so as to form a series of strut forming elements in the web, forcing the parallel edges of the member apart so as to stretch the elements and thus form struts, the edge portions thereby becoming chords, and positioning load transmitting members between chords so as to transmit load imposed on one of the chords to the other chord.

EXPANDED STRUCTURAL MEMBERS

This invention relates to improvements in expanded structural members wherein truss-like members are formed as spaced outer chords interconnected by a plurality of struts.

If a structural member is formed by a method which includes firstly forming a member of ductile metal having a constant cross-sectional shape which comprises a pair of spaced parallel longitudinally extending edge portions and a web joining those web portions, and the web is pierced with a plurality of spaced partly longitudinal rows of openings which overlap one another, and the deformable elements of the web between the edge portions are strained to form a series of inclined struts, then a structural girder of lattice or half lattice type is formed which is suitable for load bearing. One of the requirements of such a girder is that the metal should be sufficiently ductile to allow the struts to be formed by elongating, the elongation process normally being a simple straining process, and elongation beyond the yield point, while hardening the metal forming the struts, nevertheless can result in a slight degree of "necking", that is, reduction in diameter at a localised point. Thus the factor of safety should be increased beyond that normally used for a girder of similar configuration and dimension but made by a fabricating process, although even with an increase of factor of safety the cost of production is very small. If such a girder is tested to destruction, destruction will occur due to buckling of the chords which are in compression or of the struts which are in compression. As is well known in the art the shear loading on the girder or truss is resisted by transformation into compressive and tensile forces in the elements which define the triangles of the truss.

When a truss is formed from a unitary piece of metal by the method briefly described above, quite clearly it is desirable that the metal section should not be excessively massive because of the amount of force required to elongate the strut forming portions of the web.

Thus there are at least two reasons why the buckling loads on the chords and struts should be as small as possible for a given truss configuration, and the main object of this invention is to provide a method of forming a truss whereby the buckling forces are, substantially reduced, and in one of its forms the invention consists of the method of forming an expanded structural member which comprises forming a member of ductile metal having a constant cross-sectional shape which comprises a pair of spaced parallel longitudinally extending edge portions and a web joining the edge portions, at least partly piercing at least two spaced parallel longitudinally extending rows of openings in the web, the openings of each row overlapping those of the next adjacent row so as to form therebetween a series of deformable elements of the web interconnected by junction portions, urging the edge portions apart so as to extend the lengths of the deformable elements to thereby form struts and form chords of the edge portions, positioning at least one load transmitting member between the chords, and securing opposite ends of the load transmitting member in load transmitting relationship with the flanges to thereby transmit at least portion of a load imposed on one of the chords in the direction of the other chord to said other chord through said load transmitting member.

The invention also relates to an expanded structural member which is formed by the method of the invention, and comprises chords and struts of a unitary piece of metal and load transmitting members extending between the chords where they are joined to struts. As is shown hereunder, the existence of these load transmitting members will reduce the buckling loads very considerably if the load transmitting members are stiff spacer members which extend between the chords of the truss to transmit load from a first chord to a second chord at the location of the intersection of the struts with the second chord, or if they are plates which engage the chords along their edges.

The invention is described hereunder in further detail with reference to and is illustrated in the accompanying drawings in which:

FIG. 1 is a perspective view showing a member of ductile metal having a constant cross-sectional shape but having been pierced with three spaced parallel longitudinal rows of openings in its web,

FIG. 2 is a side elevation showing the member of FIG. 1 after the edge portions thereof have been urged apart to form chords and to simultaneously extend the lengths of deformable elements of the webs and thus form them into struts inclined to the chords, FIG. 2 showing in dotted lines one mode of inserting load transmitting members between the chords,

FIG. 3 is a section taken on line III—III of FIG. 2 wherein the load transmitting member is represented as a stiff spacer of timber,

FIG. 4 is a section on line IV—IV of FIG. 2 illustrated as the load transmitting member, a stiff spacer member formed from square section tube,

FIG. 5 is a schematic diagram showing the tensile and compressive forces in a half lattice girder when used as a beam, loaded from the top and supported at its ends from the bottom,

FIG. 6 is a similar diagram of the same half lattice girder when inverted, under the same loading and similarly supported, the half lattice girder however being modified with stiff spacer members, FIG. 6 then showing loadings which may be compared with those of FIG. 5,

FIG. 7 is a partly sectioned perspective view showing a further embodiment wherein the load transmitting members are formed by continuous plates, and

FIG. 8 shows a still further embodiment wherein the load transmitting members are formed by stiff spacer members of timber, and wherein the chords also contain timber, FIG. 8 being a truss suitable for use in buildings.

The first embodiment refers to FIGS. 1, 2, 3 and 4, and in FIG. 1 a member 30 of ductile metal is formed by an extrusion process, in this embodiment the metal being a ductile grade of aluminium alloy. The member has edge portions constituted by flanges 31 which are interconnected by a web 32, the web 32 having extending along it a pair of ribs 33, and a series of openings 34 are pierced in the web 32, there being three rows of openings 34 one between the ribs 33 and one on each side of each of the ribs. The openings of each row overlap as shown in FIG. 1 so as to form those portions of the ribs 33 which lie between the overlapping portions of the openings 34 into a series of deformable elements which are designated 35.

FIG. 2 shows the next stage in the formation of the truss wherein the flanges 31 are urged apart so as to

thereby strain the deformable elements 35 beyond their yield point, lengthening them and forming the inclined struts 36, the struts 36 being interconnected by junction portions 37 which also interconnect the struts 36 to the web 32 as illustrated in FIG. 2, the flanges 31 then becoming the chords of the truss so formed. It will be noted that the central axes of the struts 36 intersect, and it is important to arrange the length of junction portions 37 so that this will occur.

In this invention the flanges 31 have interposed between them a series of load transmitting members, and FIG. 3 illustrates one form which the load transmitting members may take. In FIG. 3 the load transmitting member is a stiff spacer member 40 which has grooves 41 in its upper and lower ends, the grooves 41 being positioned over the ribs 33 where they are joined to the web 32 by the junction portions 37. Fastening members 42 secure the ends of the stiff spacer members 40 against possible displacement. The spacer members 40 are positioned as shown to have their ends over the junction portions 37 in order to avoid placing bending moments on those portions of the flanges 31 which are unsupported by the struts 36. The struts 36 are inclined as shown in FIG. 2 at an angle of less than 45° to the flanges 31 so that the spaces designated 43 are of diamond shape have greater length than height and this enables the spacer members 40 to be inserted and then rotated, the members 40 thus being easily positioned between the flanges 31.

The slight variation of structure illustrated in FIG. 4 is useful when an all metal construction is required, and the stiff spacer member 45 is a tubular member formed from square section tube again having grooves 41 positioned over the ribs 33 and the junction portions 37. Rivets 46 secure the ends of the spacer member 45 against displacement.

The advantage of the invention is shown by comparing the loadings in the chords and struts, FIG. 5 showing a load of thirty kilograms divided into three equal portions of the junction portions between the struts and top chord of a half lattice girder which can be formed readily by this invention, and it will be seen that the end struts designated 49 each carry a compressive loading of twenty-five kilograms while the top chords designated 50 each carry a compressive loading of 26.6 kilograms. The figures shown alongside each of the elements of the chords and each of the struts indicate respective loadings and the letters "c" and "t" indicate compressive and tensile stresses respectively. If FIG. 5 is compared with FIG. 6, it will be seen that the maximum compressive loading in the struts is 10.7 kilograms in each of the struts designated 51, although the maximum compressive loading in the upper chords 52 remains substantially unaltered. This reduction of loading is achieved by the stiff spacer members which are all designated 54 in FIG. 6.

In FIG. 7 which illustrates a further embodiment of the invention, the expanded structural member generally designated 57 includes upper and lower flanges 58 and 59 respectively and an intermediate strut 60, the flanges 58 and 59 being joined by the struts 60 as in the other embodiments. The upper and lower flanges however each have inwardly facing beads 61 arranged in two pairs in each flange and defining between them four channels, channels on respective sides of the strut 60 retaining upper and lower edges of a shear plate 62 on each side, the shear plate 62 being inserted by

straining the intermediate struts 60, positioning each shear plate 62 in its respective lower channel, and releasing the strain on the struts 60 so that the resilience thereof draws the other channels into engagement with the other edges of the shear plates 62. The advantage of the structure which is illustrated in FIG. 6 is even greater when the load transmitting members are shear plates as shown in FIG. 7, and the load on the shear plates is so small that decorative panels in some instances are used.

In many building operations it is desirable to provide timber vertical and horizontal members for the fixing of roofing purlins or other scantlings, and in the further embodiment illustrated in FIG. 8, the flanges again designated 31 are interconnected by inclined struts 36 as in the embodiment of FIG. 2, the struts 36 being joined together and also being joined to the web 32 by the junction portions 37. The flanges 31 however have upstanding edges 65 which perform the dual function of retaining timber chord inserts 66 and also stiffening and strengthening the chords which are constituted by the flanges and the inserts. The load transmitting members are again stiff spacer members 67 each formed in two portions joined together by fastening means 68, the members 67 also being of timber and extending for the full width of the flanges 31 so as to facilitate securing of other structural or decorative members required.

In all the above embodiments the member of constant cross-section has been described as having openings pierced therethrough. The openings need not be completely pierced, but if desired the slugs formed by piercing of the openings may be only partly sheared, and removed upon the urging of the edge portions apart. In all cases the edge portions are urged apart by clamping between jaws which themselves are driven apart under hydraulic pressure.

It should be noted that difference in truss configuration, strut length, or loading will produce substantial variations to the loadings shown in FIGS. 5 and 6.

What I claim is:

1. The method of forming an expanded structural member which comprises extruding a member of ductile metal having a constant cross-sectional shape which comprises a pair of spaced parallel longitudinally extending edge portions, a web joining the edge portions, and at least one rib extending along the web, at least partly piercing at least two spaced parallel longitudinally extending rows of openings in the web, each opening being a slot having parallel sides and curved ends, the openings of each row overlapping those of the next adjacent row so as to form therebetween a series of deformable elements of the web interconnected by junction portions, said deformable elements each comprising portion of a said rib,

urging the edge portions apart so as to extend the length of the deformable elements to thereby form struts and form chords of the edge portions, and positioning at least one load transmitting member between the chords, and securing opposite ends of the load transmitting member in load transmitting relationship with the chords to thereby transmit at least a portion of a load imposed on one of the chords in the direction of the other chord to said other chord through said load transmitting member.

2. The method according to claim 1 wherein said load transmitting member is a plate, and the method comprises the further step of securing the plate along two opposite edges to respective edge portions.

3. The method according to claim 2 wherein said chords comprise flanges each having two pairs of inwardly directed beads with a pair on each side of said struts, each pair of inwardly directed beads forming a channel therebetween, said method comprising the further step of straining the struts, positioning each of two said plates between the channels on respective sides of the struts, and releasing the strain on the struts whereby the resilience of the struts retains the edges of the plates in respective channels.

4. The method according to claim 1 wherein each load transmitting member is a stiff spacer member extending between the chords, the method further comprising engaging at least one end of each load transmitting member with one of the chords at the location of a junction portion between that chord and a said strut.

5. The method according to claim 4 wherein flanges comprise said chords, the method further comprising interpositioning each said stiff spacer member between the flanges and securing it thereto.

6. The method according to claim 4 wherein each spacer member contains grooves in its ends, the method further comprising positioning the grooves over the struts at the location of junction portions between the struts and the edge portions.

7. The method according to claim 4 wherein said spacer members are formed of timber.

8. The method according to claim 4 wherein said spacer members are formed of tubular metal having a square cross-sectional shape.

9. The method according to claim 1 wherein the edge portions are channels which contain timber.

10. The method according to claim 1 comprising at least partly piercing more than two said spaced parallel longitudinally extending rows of openings in the web to thereby form a plurality of said series of deformable elements of the web interconnected by said junction portions, and urging the edge portions apart so as to extend the lengths of the deformable elements to thereby form a plurality of struts interconnected by said junction portions and having the central axes of the struts intersecting in the junction portions.
